PUZZLE-LOCK

Rudolf Heimers, Mexico, D. F., Mexico

Application July 24, 1934, Serial No. 736,761
In Mexico July 25, 1933

3 Claims. (Cl. 273—153)

The invention refers to a puzzle-lock adapted to be used for covers, envelopes, boxes, bottles, containers and objects of all kinds, and has for its object to provide a lock which at first sight seems very easy to open but which is so arranged as to require time, patience and ingenuity to arrive at the solution of its intricacies, permitting it to be opened without breaking any of its parts.

The puzzle-lock may for instance be used with covers, envelopes or wrappers containing advertising matter, which in this case will not be thrown away without opening, due to the natural desire of humans to solve a riddle presented to them. The same lock, with slight variations, may also be used with all kinds of boxes, bottles and containers so as to prevent them from being opened by unauthorized people, although their contents will be readily accessible to those knowing how to open the lock.

20 In the accompanying drawing:

Figure 1 shows the lock applied to a cover or envelope.

Figure 2 shows the folds of the envelope extended.

25 Figure 3 is a view of the cardboard insert forming the lock.

Figure 4 shows the insert placed in the envelope, with the covering fold cut away.

Figure 5 shows the insert slid upwardly preliminary to opening the lock.

Figure 6 is a side view of the envelope with the flap pulled through the slot for removing the seals.

Figure 7 shows the same lock applied to a box.

Figure 8 represents a bottle provided with a similar lock.

Figure 9 shows the upper part of a bottle with a different kind of cover.

Figure 10 is a view of a bottle covered by a cup and a puzzle-lock for removing said cup.

Figure 11 shows an insert to be moved in two different directions for opening.

In Figures 1 to 6 there has been shown an envelope 1, of any size and material, closed on three sides and having a long flap 2 extending from its narrow open side and provided with two longitudinal slots 3. This flap passes in and out of the envelope through two slots 4 and 5, and through its slots 3 is drawn a string or ribbon 6, the ends of which pass through a small notch 7 in the center of a transversal slot 8 extending through both sides of the envelope, each end of the string 6 carrying a seal 9 of a diameter slightly smaller than the length of the slot 8. The extremity of the flap 2 extending beyond the

slots 3 is preferably inserted into another slot 10, preventing it from being torn off. Another longer slot 11 passes through both sides of the envelope, above the slot 8, and a round opening 12 is also provided in both faces of the envelope. Within 5 the envelope is placed a paper or cardboard insert 13 having a wide slot 14 corresponding with the slots 11, a rounded recess 15 corresponding with the notch 7 in the slots 8, and outwardly curved lower edges starting from said recess 15. The 10 length and width of the insert 13 are such that it fills out completely the inner space of the envelope, as shown in Figure 4, with the recess 15 straddling the opening 7 and the lower part of the insert, at the sides of said recess, covering 15 from the inside the slots 8, leaving exposed only the opening 7 through which passes the string 6.

The puzzle consists in separating the string 6 from the slots 3 so that the flap 2 may be raised and the contents of the envelope taken out, but 20 without tearing any of its parts. The solution seems to be to pass the seals 9 through the superposed slots 8, but this cannot be done as the insert covers these slots on both sides and as also 25 the diameter of the seals may be greater than the length of said slots. The slots 11 are also covered from the inside by the same insert, as are also the round openings 12.

The solution consists in sliding or raising the flap 2 into the position shown in Figure 5, so 30 that the insert 13, through the openings 12, may be pushed upward into the bend formed now by said flap. The lower part of the insert 13 is thereby raised and uncovers the slots 8. The envelope is now doubled as shown in Figure 6, the 35 flap 2 is passed through the slots 8 and the string 6 with its seals 9 can be withdrawn from the slots 3.

The insert 13 may also be made slightly shorter than the length of the envelope, as shown by a 40 dotted line in Figure 3, and, fitting rather tightly into the envelope, can be pushed up against the doubled flap 2, also uncovering the slots 8.

The lock is not necessarily applied only to containers, as it may also be incorporated for instance in a book mark which will readily be kept as such or used for entertaining other people. In this case, the envelope is preferably made narrower and the upper part of the flap 2 may be glued in place. One of the openings 12 may be 50 omitted and in its place the insert 13 may have an opening concentric with the opening 12 left.

Figure 7 shows the same puzzle-lock adapted to a box 16 having a cover 17 hinged along one of its long sides. The cover 17 is made up of two 55

layers of material, between which slides the insert 13 provided with an opening 18 concentric with the opening 12 in the upper layer of the cover, so as to enable the insert to be pushed up more easily. The flap 2 with its slots 3 is attached to a sliding cover 19 holding the box shut, and the slots 8 are placed close to the edge of the cover 17, the side wall of the box 16 being set back of said slots. As in the envelope lock, the flap 2 is pushed through the slot 8, after the same has been uncovered by sliding the insert 13 towards the opposite end of the box, and the string 6 may then be easily removed. The sliding cover 19 is taken off and the box may be opened.

15 The bottle shown in Figure 8 has a cover piece 20 preventing the cork from being pulled out, said cover being attached to a band 21 surrounding the neck of the bottle and having in each extremity a slot 22, both extremities passing through a slot 20 in the front part of the cover 20. A wire 23 with seals 24 at its ends is drawn through the slots 22 and passes through a hole provided in a flap 25 extending obliquely from a wide band 26 surrounding the bottle at the part generally occupied by the label and also formed of two layers of material, between which slides the insert 27. This insert also carries a nose 28 with a recess (15) shown in Figure 3, which straddles the hole through which is threaded the wire 23 and closes the slot extending from said hole, passing between the two layers of the flap 25. By pushing the insert upward, by taking hold of the opening 29 appearing through the bigger opening 30 in the band 26, the slot provided in the flap 25 is uncovered and the seals 24 may be withdrawn. The cover 20 is taken off and the bottle can be opened. A metal strip 31 passing around the bottom of the bottle and entering with its doubled ends into slots provided in the band 26 keeps the latter in place.

Figure 9 shows a different kind of cover 20^a for the top of a bottle, the end of which is provided with two longitudinal slots 32 and which is held in place by an annular band 33. The wire 23 may be drawn through these slots 32 and the lock operated as explained with relation to Figure 8.

As shown in Figure 11, the insert 27, displaceable in suitable guides 34, may have two openings 35 and 35^a having each a step cut out in one side. The doubled extremities of the strip 31 passing under the bottom of the bottle are detained on said steps when the strip 31 is pressed into the hollow bottom of the bottle, as shown in Figure 10. The seals 24 in this case are of a greater diameter than the slot 8 in the flap 25, so that they cannot be extracted through said slot even if uncovered by the insert (13) which is fastened slidingly to the insert 27. For opening the lock, the insert 13 is first pushed upward, carrying with it the insert 27, whereby the portion of the strip 31 entering the hollow bottom is straightened, permitting the annular band 26 to be moved upwardly. The insert 27 is then pushed towards the right so that the ends of the strip 31 leave

the steps in the openings 35 and 35^a and enter the downwardly extending space in said openings, whereby said strip 31 having become longer, may be swung to one side of the bottle. The band 26 can now be raised until the flap 31, preferably longer than shown in Figure 9, may be passed through the slot in the flap 25, uncovered by this time, and the seals 24 with the wire 23 withdrawn from the slots 32.

Finally, Figure 10 shows a bottle, the neck of which is covered by a cup 36. To this cup is attached at one side or at opposite sides a strap 37, the lower extremity of which is expanded into a flat round seal 38. This seal is passed through a slot 8 in the band 26 encircling the bottle and is prevented from being withdrawn by the recessed lower edge of the insert 13. By pushing this insert upward, by means of its openings 29 appearing through the larger openings 30 in the band 26, the slot 8 is uncovered and the seal 38 may be passed through it.

What I claim is:

1. A puzzle-lock, comprising a member having two superposable portions, which have superposable slots therein, an insert slidably disposed between said portions, shaped to partially close said slots in one of its positions, and adapted to uncover said slots when moved to another position, and locking means passing through said slots and prevented from being withdrawn by the insert when in its closing position.

2. A puzzle-lock, comprising a member having two portions which are superposable and which, when superposed, provide an inlet to the space between them, said portions having superposable slots therein, an insert between said portions and shaped to partially close said slots, said insert being slidable to a position in which it uncovers said insert, means whereby said insert may be displaced from the outside, a slotted flap covering the said inlet between said portions, and flexible means passing through the slots of said flap and provided at their ends with portions having enlarged surfaces, said flexible means passing through said slots when they are superposed and said portions being withdrawn through said slots after the latter have been uncovered by said sliding insert.

3. A puzzle-lock, comprising a cover, having two portions which are superposable and which have superposable slots therein, an insert slidably disposed within said cover and shaped to partially close said slots in one of its positions, and adapted to uncover said slots when moved to another position, there being openings in said cover to give access for displacing said insert from the outside, a slotted flap closing said cover, and flexible means passing through the slots of said flap and provided at their ends with seals, said flexible means passing through said superposed slots, and said seals being withdrawn through said slots after the latter have been uncovered by said sliding insert.

RUDOLF HEIMERS.
